Primary Examiner — Bridget L Eland*Assistant Examiner* — Lauren McVey(74) *Attorney, Agent, or Firm* — Seed IP Law Group LLP(57) **CLAIM**

The ornamental design for a wireless communication device, as shown and described.

DESCRIPTION

FIG. 1 is a top front right perspective view of a wireless communication device showing our new design;

FIG. 2 is a bottom rear left perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The broken lines immediately adjacent the claim represent the bounds of the claimed design while all other broken lines, including the large broken line circle in FIGS. 2 and 4, are directed to environment and are for illustrative purposes only; the broken lines form no part of the claimed design.
